SHOE HOLDER

Robert H. Lawson, Beverly, Mass., assignor to
United Shoe Machinery Corporation, Paterson,
N. J., a corporation of New Jersey

Application July 9, 1930. Serial No. 466,615

37 Claims. (Cl. 12—126)

This invention relates to holders for shoes. It may usefully be employed for presenting and retaining a shoe for the attachment of its heel, though capable of other applications.

An object of the invention is to so hold a shoe for an operation upon it, that it occupies a definite position, this preferably being determined longitudinally, transversely, vertically and angularly, and requiring only simple manipulation by the operator, who need not give thought to the various relations which must be established. In accomplishing this, I employ novel means for locating the rear portion of a shoe, together with means movable against the forward portion, there being preferably opposite members movable simultaneously by the operator into engagement with the shank, for locating it transversely and angularly. This positioning action may be with respect to a pressure-abutment, as one by which a heel is held for attachment. The forward locating means, regardless of its effect upon the angular relation of the shoe, may serve to support it, as by a portion extending beneath the shoe-sole. The rear positioning means is shown as including both a back-stop, which fixes the longitudinal relation of the work, and means, as a counter-fork, which determines the transverse relation of this portion of the shoe to be held. The forward positioning means, in addition to locating the shoe transversely and angularly and supporting it as just noted, may be utilized to urge the shoe longitudinally against the back-stop. For this latter purpose, in the illustrated construction the opposite members grasp the shoe and then move bodily with it toward the back-stop.

Another object of the invention is to establish the correct relation for the operation upon it of a shoe held as above outlined. The holder has associated with it a last-support, and the support and holder, the latter carrying a shoe in which is a last, are relatively movable to bring into contact the support and last. With the work thus positioned, the holder may be locked to prevent separation of the last and support. Means is disclosed for actuation by the operator to unlock the holder at the completion of the operation upon the work. This release is conveniently effected through the member by which the operator actuates the shoe-positioning means.

In the accompanying drawings,

Fig. 1 is a top plan view of a particular embodiment of my invention;

Fig. 2 is a side elevation thereof with a lasted shoe positioned by the holder;

Fig. 3 shows my improved organization in end elevation looking from the right in Fig. 2, the elements being in their normal relation without a shoe; and

Fig. 4 is a vertical sectional detail on the line 60 IV—IV of Fig. 2.

At A appears a base, consisting of a vertical portion 10 and a generally rectangular top-plate 12. The plate may be adjustable horizontally thereon along ways 14. Rising from this plate 15 is a post 16, having, upon a universally movable bed-plate, an upper surface 18 furnishing a support for the cone of a last contained in a shoe to be operated upon.

The base also has mounted upon it a holder 70 for the work. Near each corner of the plate 12 is a standard 20, and between the forward and rear pairs of standards are respectively fulcrumed levers B and C, each consisting of a pair of outer approximately horizontal arms 22, 22 75 and a depending central arm 24. Pivoted upon the arms 22 is a horizontal carrier frame 26 at the rear of which is an upwardly extending portion 28. At the center and upon the top of this portion 28 is secured a gage member in the form 80 of a back-stop 30 having a forward reduced edge arranged to enter the rand-crease of a shoe near the center of the counter-portion. A gage-fork has an arm 32 pivoted upon the portion 28 at each side of the back-stop, a rounded end 34 of 85 each arm being arranged to engage the counter-portion of the shoe below the rand-crease. Intermeshing teeth 36 connect the arms of the fork to oscillate together, and they are forced into engagement with the shoe by spring-actuated plungers 38, 38 movable horizontally in the carrier-portion 28. By these fork-arms, a shoe longitudinally positioned by the back-stop 90 has its rear extremity located in a definite transverse relation.

Guided in horizontal depressions at the outer sides of the carrier-portion 28, below the back-stop and the fork, is a slide 40 of U-form, its arms extending forwardly and normally urged in this direction by a spring 41. This spring is shown 100 as of the leaf-type secured at its lower end to the plate 12 and resting at its upper extremity against the slide. At the forward end of each arm of the slide, a bell-crank lever D is fulcrumed upon a vertical axis. An upwardly and 105 forwardly extending arm 42 of each lever has an inner contact member 44 lying in a plane just above the back-stop 30. As best shown in Fig. 4 of the drawings, this contact-end of each lever has a depression between horizontal inward pro- 110

jections 46, 46. The width of the depression is such as to receive the edge of the sole of a shoe to be operated upon, the lower projection supporting the weight of the forepart of the shoe 5 and the upper preventing its upward displacement. Each lever D possesses an inwardly and downwardly inclined arm 48, joined by a link 50 to a slide E, made up of a cross-bar 52, to the opposite ends of which the links are articulated, 10 and a plunger 54 guided in a bore in the forward extremity of the carrier 26. Rising above the plunger 54 is a projection 56, entering a cam-slot 58 in a segmental extension 60 from a hand-lever 62 fulcrumed for horizontal movement 15 upon the carrier above the plunger 54. The contact members 44 of the levers D are located opposite that portion of the sole of a shoe carried by the holder, which has its edges substantially parallel and equidistant from the longitudinal axis of the shoe-bottom. The sole-receiving depressions of the contact members are 20 equally spaced from the longitudinal center of the holder, with which the axis of the shoe is to be made to coincide, and are oscillated oppositely at equal rates by their connection to the hand-lever 62. Consequently, when the levers D are 25 swung in by pulling the hand-lever forward, their contact-members, upon engagement with the sole of the shoe positioned at the rear by the back-stop and counter-fork, will move said shoe in the direction necessary to establish its desired angular relation and the transverse position of the forepart, and will retain it against vertical displacement by the engagement of the projections 30 46, 46 with the opposite sides of the sole or the sole and welt. After the cam-slot 58 has thus thrust the contact-portions of the levers D against the opposite edges of the sole, continued pull upon the hand-lever applies to the levers 35 D forces tending to push back the slide 40 against resistance of the spring 41, shifting the levers D bodily in this direction. This causes the lever-portions 44 to be simultaneously pressed upon the sole-edge and moved rearwardly over it. 40 As a result, the rear of the shoe is seated firmly against the back-stop and is now correctly positioned in all directions. The contour of the slot 58 is such that frictional engagement between the projection 56 and the slot-wall retains the hand-lever against accidental rearward movement, and the work locked in the holder until the operator shifts the lever in the opposite direction. 45 In operations of the character of heel-attaching, it is customary to apply a measuring pressure to the work, to establish a definite initial relation to the operating instrumentalities regardless of the height of the last and the thickness of the shoe-parts, and then to impose a final clamping pressure in preparation for driving the attaching nails. My improved work-holder is organized to cooperate with pressure-receiving means. The particular form of such means and the manner of its action is of no consequence, as far as this invention is concerned. I have illustrated a portion of a head F adapted to act as a pressure-abutment. This head may be provided with any suitable heel- or lift-holding and nail-driving means. To create the pressure between the thus-supported heel and the heelseat of a shoe in the holder, the base A, with the holder, may be elevated by such mechanism as that acting upon the Jack of Letters Patent of the United States No. 446,885, Pope, Feb. 24, 1891. Ascent of the holder, under the influence of the treadle 50 75

mechanism of the Pope patent, with the consequent contact of the heelseat of the shoe in the holder with the heel carried by the head, will lower the carrier 26. The carrier is normally elevated, with the shoe-engaging elements at 80 their maximum height above the surface 18 of the post 16, by a spring 70, surrounding a rod 72 joining the arms 24 of the levers B and C. This spring exerts its expansive force upon an enlargement of the rod and against the post 16, 85 through an opening in which post the rod passes. Contact of an enlargement at the end of the rod opposite the spring with the outer side of the post limits the upward movement of the holder. Said holder is preferably releasably locked against 90 reverse movement, away from the support-surface 18, by a latch 74 pivoted upon the base-plate 12 and forced by a spring-actuated plunger 76 against a series of teeth 78 formed upon the under side of a portion of the rod 72. The teeth are so 95 inclined that during the depression of the holder under the influence of the head F they slip over the pawl, but are held against the reverse movement by the engagement of said pawl. When the holder is thus locked, the final pressure may be 100 applied by further elevation of the base A under power, this forcing the work more firmly against the nailing head F as an abutment. After the nailing, or other operations, have been performed upon the shoe in the holder and the clamping 105 pressure released, the operator pushes rearwardly the lever 62. Extending from the under side of the plunger 54, below the projection 56, is an arm 80 fast upon the plunger. The lower extremity of the arm is united by a pin-and-slot 110 connection 82 to a link 84, the opposite end of the latter being articulated to a depending portion of the latch 74. The pin of the connection 82 bears such a relation to its slot that during the forward holder-actuating movement of the hand-lever it travels idly. Upon the opposite or rearward movement of the lever, when the operator releases the shoe from the holder, the pin strikes the rear extremity of the slot, and before the forward end of the cam-slot 58 has reached the 120 projection 56 it disengages the latch 74 from the teeth 78, freeing the rod 72. The spring 70 thereupon expands to restore the carrier and shoe-engaging elements to their normal elevated positions. 125

To sum up briefly the operation of the holder, the operator places a shoe S with the rear edge of its sole s above the stop 30 and its counter-portion between the fork-arms 32, and forces it back until the stop is seated in the rand-crease 130 and the fork-arms are opened by the pressure of the counter-portion against the ends 34. The shoe is thus located in a substantially correct longitudinal relation by the entrance of the stop 30 into the crease and laterally as to its rear portion by the pressure of the fork-arms 32 actuated by their plungers 38, and it is also positioned and retained against vertical displacement at this position by the presence of the stop in the crease. This having been accomplished, the 140 operator raises or lowers the forepart of the shoe as may be necessary to horizontally align its sole-edge with the depressions in the contact portions 44, 44 of the normally separated levers D, D, and pulls forward the hand-lever 62. Consequent 145 rearward movement of the plunger 54 and its connections swings the arms 42 of the levers D, D until the projections 46 of their contact portions embrace the sole-edges at points equally separated from the longitudinal axis of the shoe- 150

bottom. Upon this engagement, the oscillation of the levers D ceases, and continued movement of the hand-lever by the operator causes rearward travel of the slide 40 against its spring 41, carrying the lever-arms 42 and their contact-portions along the sole-edge. The effect of this is to more firmly seat the work against the back-stop, fixing it in the correct longitudinal relation. The position of the forepart, considered both transversely at right angles to the longitudinal axis of the shoe and angularly above a pivotal point at the back-stop, was attained upon termination of the inward movement of the contact-portions of the levers. The operator may now release the hand-lever, which locks the movable shoe-engaging elements of the holder, and may proceed with whatever operation is to be performed upon the shoe. If this involves the attachment of a heel H, said heel is placed in the head F and the base A raised by the operator as in the previously-mentioned patent. Contact of the heelseat of the shoe S with the heel holds the carrier 26, compressing its spring 70, until the cone of the last L contained in the shoe 25 and the top 18 of the post 16 contact. The work thus having been measured or placed under preliminary pressure, the machine with which the holder is associated may be actuated to apply the final pressure and drive the nails contained in the head F. The operation being completed, depression of the base 10 frees the carrier and holder; whereupon the operator may restore the elements of the holder to their normal relation by swinging the hand-lever back as is shown in Fig. 1. This causes the arms 42 of the levers D to carry the contact-portions 44 away from the sole-edge and the latch 74 to release the rod 72, the spring 70 elevating the holder. The operator can then draw the heeled shoe from between the fork-arms 32 and clear of the back-stop, removing it from the holder, which is ready for the reception of the succeeding piece of work.

Having described the invention, what I claim as new and desire to secure by Letters Patent of the United States is:

1. In combination, a shoe-holder comprising means for locating the rear portion of a shoe and means arranged for movement against the forward portion of the shoe for locating it angularly, and supporting means into engagement with which is movable a last within a shoe positioned by the holder.

2. In a shoe-holder, a back-stop arranged to enter the rand-crease of a shoe to support it and to locate it longitudinally, means associated with the back-stop for locating the shoe laterally, and means arranged for movement against the shank-portion of the shoe for locating said shoe angularly.

3. In a shoe-holder, a back-stop arranged to enter the rand-crease of a shoe to support it and to locate it longitudinally, means associated with the back-stop for locating the shoe laterally, said back-stop and lateral-locating means being relatively movable, and means arranged for movement against the shank-portion of the shoe for locating said shoe angularly.

4. In a shoe-holder, means for locating the rear portion of a shoe, and means arranged for movement laterally into contact with the forward portion and thereafter rearwardly in engagement with said forward portion.

5. In a shoe-holder, a back-stop for a shoe, and opposite members arranged for movement in-

wardly and rearwardly against the forward portion of the shoe for locating it angularly and forcing it against the back-stop.

6. In a shoe-holder, a back-stop for contact with a shoe, members arranged to grasp the shoe at opposite sides, and means arranged to move the members toward the back-stop, such movement occurring while the members are in contact with the shoe. 80

7. In a shoe-holder, means for locating the rear portion of a shoe, and a lever fulcrumed at each side of the shoe and movable about its fulcrum and also bodily therewith, and means arranged to move the levers about their fulcras into contact with the forward portion of the shoe and then bodily with their fulcras in contact with said shoe. 85

8. In a shoe-holder, a back-stop for a shoe, arms arranged for engagement with opposite sides of the shank-portion of the shoe located by the back-stop, a mounting for the arms yieldable longitudinally of the supported shoe, and connections arranged to move the arms and to maintain them in the same relation transversely of the holder. 90

9. In a shoe-holder, a back-stop for a shoe, a lever fulcrumed at each side of the back-stop and having a portion for contacting with the shank-portion of a shoe, a slide connected to the levers, and a lever acting upon the slide and arranged for actuation by an operator. 100

10. In a shoe-holder, a back-stop for a shoe, a lever fulcrumed at each side of the back-stop and having a portion for contacting with the shank-portion of a shoe, a slide connected to the levers and having a projection, and a lever pivoted adjacent to the slide and provided with a cam-slot receiving the projection. 110

11. In combination, a shoe-holder comprising a back-stop for a shoe, arms provided with depressions to receive opposite edges of the sole of the shoe located by the back-stop and means arranged to move the arms together, and a pressure-abutment to which the holder presents the shoe. 115

12. In combination, a shoe-holder comprising a back-stop arranged to enter the rand-crease of a shoe, arms provided with depressions to receive opposite edges of the sole of the shoe located by the back-stop and means arranged to move the arms together, and a heel-holding abutment to which the holder presents the shoe. 125

13. In a shoe-holder, a back-stop for a shoe, a fork having yieldable arms for contacting with the counter-portion of the shoe, arms provided with depressions to receive opposite edges of the shank-portion of the sole of the shoe located by the back-stop, and means arranged to move the arms together. 130

14. In a shoe-holder, a carrier, a back-stop for a shoe mounted upon a carrier, a slide movable upon the carrier, shoe-engaging levers fulcrumed upon the slide, and connections to the levers for oscillating them upon the slide and for moving said slide. 135

15. In a shoe-holder, a carrier, a back-stop for a shoe mounted upon a carrier, a slide movable upon the carrier, shoe-engaging levers fulcrumed upon the slide, connections to the levers for oscillating them upon the slide and for moving said slide, and means for resisting movement of the slide under the influence of said connections. 145

16. In a shoe-holder, a carrier, a back-stop for a shoe mounted upon a carrier, a slide movable upon the carrier, a spring acting upon the slide, 150

- shoe-engaging levers fulcrumed upon the slide, and connections to the levers for oscillating them upon the slide and for moving said slide against the force of the spring.
- 5 17. In a shoe-holder, means for locating the rear portion of a shoe, and a lever fulcrumed at each side of the shoe for inward and rearward movement in contact with the forward portion of said shoe. 80
- 10 18. In a shoe-holder, means for locating the rear portion of a shoe, and a shoe-supporting lever fulcrumed at each side of the shoe for inward and rearward movement into contact with the shank-portion of said shoe. 85
- 15 19. In a shoe-holder, means arranged to locate the rear portion of a shoe and to support its sole, and a member arranged for engagement with the forward portion of the shoe-sole and provided with a shoe-supporting portion extending beneath said sole for contact therewith. 90
- 20 20. In a shoe-holder, means for locating the rear portion of a shoe, and a member movable inwardly and rearwardly in contact with a portion of the shoe-sole and provided with a shoe-supporting portion extending beneath said sole. 95
- 25 21. In a shoe-holder, a back-stop for a shoe, and opposite members arranged for movement inwardly and rearwardly against the forward portion of the shoe for locating it angularly and 100 forcing it against the back-stop, said members having portions extending above and below the sole. 105
- 30 22. The combination with a last-support, of a shoe-holder, said support and holder being relatively movable to bring into contact the support and a last within a shoe carried by the holder. 110
- 35 23. The combination with a last-support, of a shoe-holder, said support and holder being relatively movable to bring into contact the support and a last within a shoe carried by the holder, and means for securing the holder against separation of the last from the support. 115
- 40 24. The combination with a last-support, of a shoe-holder, said support and holder being relatively movable to bring into contact the support and a last within a shoe carried by the holder, a latch for the holder, and means arranged for actuation by an operator for releasing the latch. 120
- 45 25. The combination with a post, of a movable shoe-holder arranged to align with the post the cone of a last within a shoe carried by the holder, and means for securing the holder with the last-cone in engagement with the post. 125
- 50 26. The combination with a last-support, of a holder having members movable to engage a shoe, said holder and support being relatively movable to bring into contact a last within a shoe carried by the holder and the post, means for securing the holder against separation of the last and post, and a member arranged for actuation by an operator to move the shoe-engaging members of the holder and to control the securing means. 130
- 55 27. The combination with a post, of a holder having members movable to engage a shoe, said holder being arranged to align with the post the cone of a last within a shoe carried by the holder, a latch for securing the holder with the last-cone in engagement with the post, and a member arranged for actuation by an operator to move the shoe-engaging members of the holder and to release the latch. 135
- 60 28. The combination with a base, of a carrier movable thereon, a back-stop for a shoe fixed to the carrier, levers mounted to oscillate upon the 140
- 65 70 75 carrier for contact with opposite sides of the shank-portion of the shoe, a hand-lever fulcrumed upon the carrier, and connections between the hand-lever and shank-contacting levers. 145
- 75 29. The combination with a base, of a carrier movable thereon, a back-stop for a shoe fixed to the carrier, levers mounted to oscillate upon the carrier for contact with opposite sides of the shank-portion of the shoe, a hand-lever fulcrumed upon the carrier, connections between the hand-lever and shank-contacting levers, a latch for the carrier, and connections between the hand-lever and latch. 150
- 80 30. The combination with a base, of a carrier movable thereon, a back-stop for a shoe fixed to the carrier, a slide movable on the carrier, levers fulcrumed upon the slide for contact with opposite sides of the shank-portion of the sole of the shoe, a hand-lever fulcrumed upon the carrier, and connections between the hand-lever and the shank-contacting levers. 90
- 85 31. The combination with a base, of a carrier movable thereon, a back-stop for a shoe, said back-stop being fixed to the carrier, a slide movable on the carrier, levers fulcrumed upon the slide for contact with opposite sides of the shank-portion of the sole of the shoe, a hand-lever fulcrumed upon the carrier, a slide connected to the hand-lever, and links joining the slide and shank-contacting levers. 100
- 90 32. The combination with a base, of a carrier movable thereon, a back-stop for a shoe fixed to the carrier, a slide movable on the carrier, levers fulcrumed upon the slide for contact with opposite sides of the shank-portion of the sole of the shoe, a hand-lever fulcrumed upon the carrier and provided with a cam-slot, a slide having a projection extending into the slot, and links joining the slide to the shank-contacting levers. 105
- 95 33. The combination with a base, of a post rising therefrom, levers fulcrumed upon the base, a carrier mounted upon the levers, shoe-holding members mounted upon the carrier and co-operating with the post, a member connected to a mounting lever and provided with teeth, and a latch carried by the base and engaging the teeth. 110
- 100 34. The combination with a base, of a post rising therefrom, levers fulcrumed upon the base, a carrier mounted upon the levers, shoe-holding members mounted upon the carrier and co-operating with the post, a spring normally elevating the carrier to separate the shoe-holding members from the post, a member connected to a mounting lever and provided with teeth, and a latch carried by the base and engaging the teeth. 115
- 105 35. The combination with a base, of a post rising therefrom, levers fulcrumed upon the base, a carrier mounted upon the levers, shoe-holding members mounted upon the carrier and co-operating with the post, a member connected to a mounting lever and provided with teeth, a latch carried by the base and engaging the teeth, a hand-lever fulcrumed upon the carrier, and connections between the hand-lever and latch. 120
- 110 36. The combination with a base, of a post rising therefrom, levers fulcrumed upon the base, a carrier mounted upon the levers, a slide movable upon the carrier, shoe-engaging members pivoted upon the slide, a member movable with the carrier and provided with teeth, a latch carried by the base and engaging the teeth, a hand-lever fulcrumed upon the carrier, and connections between the hand-lever and the shoe-engaging members and latch. 125

37. The combination with a base, of a post rising therefrom, levers fulcrumed upon the base, a carrier mounted upon the levers, a slide movable upon the carrier, shoe-engaging members pivoted 5 upon the slide, a member movable with the carrier and provided with teeth, a latch carried by the

base and engaging the teeth, a hand-lever fulcrumed upon the carrier, a spring acting upon the slide to resist its movement by the hand-lever, and connections between the hand-lever and the shoe-engaging members and latch.
